UNITED STATES PATENT OFFICE.

ISAAC STEVENS, OF SALMON, IDAHO.

PENHOLDER.

No. 833,646.

Specification of Letters Patent.

Patented Oct. 16, 1906.

Application filed June 8, 1906. Serial No. 320,870.

To all whom it may concern:

Be it known that I, ISAAC STEVENS, a citizen of the United States, residing at Salmon, in the county of Lemhi, State of Idaho, have 5 invented certain new and useful Improvements in Penholders; and I do hereby declare the following to be a full, clear, and exact description of the invention, such as will enable others skilled in the art to which it applies 10 pertains to make and use the same.

This invention has relation to pen-ejecting penholders; and it is the object of the improvements to provide a penholder of that kind mentioned that as a new article of 15 manufacture will not only eject the pen-point when it is wanted that that thing should be done without soiling the fingers of the hand, but that will hold the pen with all desired firmness when in use and that will be 20 durable and of itself of lower cost of production.

Because of the durable properties of the pen considered in connection with its efficiency it is well adapted for employment in 25 the manufacture of penholders made out of the finer metals, such as silver or gold, though, as above stated, it is *per se* of little cost of manufacture. Being made entirely of metal it presents a neat appearance, which 30 is an incentive to the user, so that it is not likely to be lost through carelessness resulting from mislaying it, nor is it likely to be left to become befouled or clogged with ink by reason of failure to wipe it when it should 35 be given such attention.

The nature of the invention is ascertainable from the foregoing statements in view of the annexed drawings, forming a part of this specification. I will therefore proceed to 40 disclose the improvements in detail in connection with the said drawings, pointing out the invention with particularity in the subjoined claim.

Of the said drawings, Figure 1 is a longitudinal sectional view partly in elevation. Fig. 2 is a longitudinal view of the same. Fig. 3 is a separate view of the means contained in the outer tube, excepting the helical spring.

Like numerals of reference designate like parts or features, as the case may be, wherever they occur.

5 designates what I may term for the purposes of this specification the "outer" tube,

which is composed of thin sheet metal and 55 extends from near the rear or upper end to the front end. At the rear end the said outer tube contains a helical spring 6, that is inclosed in a short inner tube or cap 7 and rests at its rear end on the cap and at its forward end on a stop 8, which may be a ledge or similar device secured at its outer edge to the inner surface of the outer tube. A rod 9, attached at its rear end to the cap 7 and extending forward through the helical spring 60 6 to the grip-plate 10, is connected to the rear end of said plate and moves it forward when the rod is moved forward against the stress of the spring 6 by pressure on the cap 7. When pressure by the finger on the cap 70 is released, the spring will return the grip-plate and rod back to normal position.

The grip-plate has an upwardly-inclined slot 11 formed in its forward end. The rear end of the grip-lever 12 is slotted, and the 75 forward end of the grip-plate extends into said slot. A cross pin or projection connected with the grip-lever extends into the inclined slot 11. The said grip-lever is pivoted or fulcrumed at 13 on projections punched 80 outwardly from the sides of the semicylindrical part 14, with which the grip-lever at its forward end terminates. The said projections extend into indentations formed by punching the metal of the outer tube outwardly. The forward terminus 14 of the 85 grip-lever 12 holds the shank of the pen-point between its upper side and the upper inner side of the outer tube, the latter having about half of its otherwise cylindrical part 90 removed by a quill-pen cut, as at 15. In the upper edges of the remaining metal there are formed notches 16, into which the edges of a small strip 17, of metal, secured to the front end of the grip-lever, extend and rest on the 95 lower edges of the shank of the pen-point and assist in gripping it.

When a pen-point is in place and gripped, as stated, and it is desired to release it, the end of the forefinger will be placed on the cap, and the rod 9 and grip-plate 10 will be pushed inward against the stress of the spring 6, causing the rear end of the grip-lever 12 to be raised by the parts projecting into the upwardly-inclined slot sliding up in 100 the same, thus rocking the said lever on its fulcrum-pin 13 and depressing the forward end of the lever through the opening made in 105

the outer tube by the quill-pen cut, thereby releasing the grip on the shank of the pen-point, allowing the pen to drop.

What is claimed is—

- 5 A pen-ejecting penholder comprising an outer tube having a portion thereof cut away at its forward end and having notches formed in the edges of the remaining part, a grip-lever pivoted in the tube and having a strip on its front end disposed to engage said notches when the lever is moved in one direction, a grip-plate slidably mounted in the tube and provided with a diagonal slot with which the rear end portion of the grip-lever is slidably

engaged, a rod extending rearwardly from 15 the grip-plate, a cap upon the free end of the rod slidably engaging the rear end of the tube and projecting normally therefrom, a stop within the tube and a spring encircling the rod and bearing with its ends against the 20 cap and the stop respectively.

In testimony whereof I affix my signature in presence of two witnesses.

ISAAC STEVENS.
